[57] ABSTRACT

An improved side bank excavator for excavatingly removing earth from a hill or a bank-like area, having a horizontal earth removal assembly, a vertical earth removal assembly, and a conveyor constructed and positioned to remove the excavated earth to a remote, predetermined position, in a forward and a rearward moving direction of the excavator including a conveyor control apparatus having one portion automatically adjusting the tension of the conveyor and another portion maintaining the conveyor in a predetermined alignment position.

EXCAVATOR, CONVEYOR AND CONVEYOR CONTROL APPARATUS

REFERENCE TO RELATED APPLICATIONS

This application is a division of the Applicants' co-pending application entitled "Side Bank Excavator", Ser. No. 142,725, filed May 12, 1971, now U.S. Pat. No. 3,778,912, assigned to the assignee of the present invention.

BACKGROUND OF THE INVENTION

1. Field of the Invention

This invention relates generally to improvements in earth working apparatus and, more particularly, but not by way of limitation, to an excavator having a conveyor and conveyor control apparatus wherein the excavator excavatingly engages and removes a portion of earth from a hill or bank-like earth structure.

2. Description of the Prior Art

In the past, there have been various types of earth working apparatus designed and constructed to dig, excavate, scrape, cut and otherwise engage portions of earth to move, remove, and reshape the engaged earth for various purposes such as, for example, highway construction and land fills. In those instances where the earth must be excavatingly removed from a hillside or a bank or the like, some apparatus have been constructed to excavatingly engage a portion of the bank-like area generally along a vertical plane, while moving the earth working apparatus in a generally forward direction. When earth was excavated in this manner from a bank-like area, the earth working apparatus was generally positioned in a predetermined initial position, generally near the bank, subsequent to the earth working apparatus being moved in a forward direction, prior to each excavating pass along the bank.

In utilizing most earth working apparatus and, more particularly, the earth working apparatus of the type mentioned above which excavatingly engages a bank-like area, generally along a vertical plane, it has also been found desirable to include some device or apparatus for removing the excavated earth. In the past, for example, a belt-like conveyor has been utilized in combination with some types of earth working apparatus. The positioning and utilization of a conveyor or the like to remove the excavated earth adds yet one other additional complex factor to be considered in the construction of earth working apparatus for excavatingly removing earth from a bank-like earth structure.

SUMMARY OF THE INVENTION

One object of the invention is to provide an excavator to excavatingly engage a portion of earth generally along a vertical plane wherein the earth excavating apparatus is positionable to excavatingly engage the earth in a forward and a rearward moving direction of the excavator.

Another object of the invention is to provide an excavator to excavatingly remove earth from a bank or the like in a more efficient manner and more economical manner.

One other object of the invention is to provide a control for an earth removal conveyor automatically adjusting the tension of the conveyor to predetermined tension positions.

Another object of the invention is to provide a control for an earth removal conveyor to automatically

align the earth removal conveyor to predetermined alignment positions.

A still further object of the invention is to provide an excavator which is economical in construction and operation.

Other objects and advantages of the invention will be evident from the following detailed description when read in conjunction with the accompanying drawings which illustrate a preferred embodiment of the invention.

10

BRIEF DESCRIPTION OF THE DRAWINGS

FIG. 1 is a perspective view of an excavator constructed in accordance with the present invention.

FIG. 2 is a side elevational view of the excavator of FIG. 1.

FIG. 3 is a top plan view of the excavator of FIG. 1.

FIG. 4 is a diagrammatic view of a bank-like area of earth, taken substantially along a vertical plane therethrough.

FIG. 5 is a fragmentary, partially diagrammatic view of a portion of the excavator of FIG. 1, showing the connection of the positioning apparatus to the vertical earth removal assembly.

FIG. 6 is a partially diagrammatic, partial schematic view showing the conveyor control apparatus of the excavator of FIG. 1, utilized to automatically adjust the tension, and to automatically maintain the alignment of the conveyor.

DESCRIPTION OF THE PREFERRED EMBODIMENT

Referring to the drawings in general, and to FIGS. 1, 2 and 3 in particular, shown therein and designated by the general reference numeral 10 is an excavator which includes a support frame 12, having a cutting side 14, an earth removal side 16, a forward end 18, and a rearward end 20. It should be initially noted that the terms 35 "forward" and "rearward", as used above to designate the opposite ends of the excavator 10, and as will be used below to designate various assemblies and components of the excavator 10 and directions of movement of the excavator 10, are utilized herein for the purpose 40 of clarity of description, and such terms are relative, in that either end of the excavator 10 could be, for example, designated as the forward end or the rearward end thereof, as will be made more apparent below.

The excavator 10 and, more particularly, the support 50 frame 12 thereof is drivingly supported by a track assembly 22 which includes a plurality of endless track members 23, some of the endless track members 23 being drivingly connected to a forward power drive 24, which is supported on the support frame 12, generally near the forward end 18 thereof, and some of the endless track members 23 being drivingly connected to a rearward power drive 26, which is supported on the support frame 12, generally near the rearward end 20 thereof. More particularly, the track assembly 22 includes a first forward track assembly 28, a second forward track assembly 30, a first rearward track assembly 32 and a second rearward track assembly 34. Each track assembly 28, 30, 32 and 34 includes a predetermined number of endless track members 23, each endless track member 23 being pivotally connected to the support frame 12 via a track support member 38, for reasons which will be made more apparent below.

55

60

65

The first forward track assembly 28 includes three endless track members 23, and is connected to a portion of the support frame 12 generally near the forward end 18 and near the cutting side 14 thereof. The second forward track assembly 30, more particularly, includes a single endless track member 23, and is connected to a portion of the support frame 12 generally near the forward end 18 and near the earth removal side 16 thereof. The first rearward track assembly 32 includes three endless track members, and is connected to a portion of the support frame 12 generally near the rearward end 20 and near the cutting side 14 thereof. The second rearward track assembly 34, more particularly, includes a single endless track member 23, and is connected to a portion of the support frame 12 generally near the rearward end 20 and near the earth removal side 16 thereof.

Each endless track member 23 of the first forward track assembly 28 and second forward track assembly 30 is, more particularly, drivingly connected to the forward power drive 24, such that the forward power drive 24 drives each endless track member 23 connected thereto, to move the excavator 10 in a generally forward direction 40 and in a generally rearward direction 42. Each endless track member 23 of the first rearward track assembly 32 and the second rearward track assembly 34 is drivingly connected to the rearward power drive 26, such that the rearward power drive 26 drives the endless track members 23 connected thereto, to move the excavator 10 in a generally forward direction 40 and in a generally rearward direction 42.

The forward power drive 24 and the rearward power drive 26 thus provide the driving impetus to move the excavator 10 in a forward direction 40 and in a rearward direction 42 during the operation of the excavator 10, as will be described in greater detail below. The forward power drive 24 and the rearward power drive 26 may be of a conventional design such as, for example, a diesel powered engine, and the construction and operation of such a power unit, and the various interconnecting components and operation thereof to drivingly connect the power unit to the endless track members are well known in the art, and a detailed description thereof is not required herein.

The excavator 10 includes a grade and slope control apparatus to automatically position the support frame 12 in predetermined grade and slope positions. The grade and slope control apparatus of the excavator 10 includes a plurality of double-acting hydraulic cylinders, each hydraulic cylinder having a portion thereof connected to a portion of one of the endless track members 23 and another portion thereof connected to the support frame 12. More particularly, the grade and slope control apparatus includes three first forward hydraulic cylinders 44, 46 and 48, a second forward hydraulic cylinder 50, three first rearward hydraulic cylinders 52, 54 and 56, and a second rearward hydraulic cylinder 58, as shown more clearly in FIG. 3. Each hydraulic cylinder 44, 46, 48, 50, 52, 54, 56 and 58, includes a reciprocating piston (not shown) mounted in a cylinder (not shown), and has an actuated raising position wherein the support frame 12 is raised relative to the track assemblies 28, 30, 32 and 34, and an actuated lowering position wherein the support frame 12 is lowered relative to the track assemblies 28, 30, 32 and 34.

The excavator 10, as shown in FIGS. 1, 2 and 3, includes a horizontal earth removal assembly 60, which

is generally connected to a central portion of the cutting side 14 of the support frame 12. The horizontal earth removal assembly 60 includes a forward portion 62 which is constructed and disposed to excavatingly engage a portion of earth generally along a horizontal plane, in a forward moving direction of the support frame 12, and a rearward portion 64 which is constructed and disposed to excavatingly engage a portion of earth generally along a horizontal plane, in a rearward moving direction 42 of the support frame 12.

The excavator 10 also includes a vertical earth removal assembly 66 which is generally connected to a central portion of the cutting side 14 of the support frame 12. The vertical earth removal assembly 66 includes a forward portion 68 which is constructed and disposed to excavatingly engage a portion of earth generally along a vertical plane, in a forward moving direction 40 of the support frame 12, and a rearward portion 70 which is constructed and disposed to excavatingly engage a portion of earth along a generally vertical plane, in a rearward moving direction 42 of the support frame 12. The forward portion 68 and the rearward portion 70 of the vertical earth removal assembly 66 are each movably connected to the support frame 12 such that the forward portion 68 and the rearward portion 70 can each be positioned to an earth engaging position, as shown in FIGS. 1, 2 and 3 with respect to the forward portion 68, and to a storage position, shown in FIGS. 1, 2 and 3 with respect to the rearward portion 70, for reasons and in a manner to be described in greater detail below.

The vertical earth removal assembly 66, as described generally above, also includes a forward positioning assembly 72, which has a portion thereof connected to the forward portion 68 and another portion thereof connected to the support frame 12. The forward positioning assembly 72 is constructed and connected to the forward portion 68 of the vertical earth removal assembly 66 to move the forward portion 68 to an earth engaging position, as shown in FIGS. 1, 2 and 3, wherein the forward portion 68 excavatingly engages a predetermined portion of earth, and to move the forward portion 68 to a storage position, similar to that shown in FIGS. 1, 2 and 3 with respect to the rearward portion 70.

The vertical earth removal assembly 66 also includes a rearward positioning assembly 74, having a portion thereof connected to the rearward portion 70 and another portion thereof connected to the support frame 12, to position the rearward portion 70 in an earth engaging position, similar to that shown in FIGS. 1, 2 and 3 with respect to the forward portion 68, wherein the rearward portion 70 excavatingly engages a predetermined portion of earth, and to move the rearward portion 70 to a storage position, as shown in FIGS. 1, 2 and 3.

As shown in FIGS. 1, 2 and 3, the excavator 10 includes a conveyor assembly 76 having a belt-like conveyor 78 supported via a conveyor support frame 80, which extends angularly generally over the support frame 12, generally between the cutting side 14 and the earth removal side 16 thereof. The conveyor 78 has a receiving end 82 and a disposing end 84, and is disposed and constructed to move the excavated earth deposited thereon generally toward the disposing end portion 84 thereof, and to deposit the excavated earth so moved by the conveyor 78 in a predetermined area,

that is an area generally determined by the disposition of the disposing end 84 of the conveyor 78.

The receiving end portion 82 of the conveyor 78 is disposed generally between the forward portion 62 and the rearward portion 64 of the horizontal earth removal assembly 60, and generally between the forward portion 68 and the rearward portion 70 of the vertical earth removal assembly 66. The receiving end portion 82 of the conveyor 78 is thus disposed to receive the earth excavated by the horizontal earth removal assembly 60 and the vertical earth removal assembly 66, in a forward moving direction 40 and a rearward moving direction 42 of the support frame 12, during the operation of the excavator 10, in a manner to be described in greater detail below.

The conveyor assembly 76 includes a conveyor drive 86 which is drivingly connected to the conveyor 78, generally near the disposing end 84 thereof, to drive the conveyor 78 in a direction generally from the receiving end 82 toward the disposing end 84 thereof, in an actuated position of the conveyor drive 86.

It should be particularly noted that the belt-like conveyor 78 is, more particularly, of the endless belt type and the conveyor drive 86 is thus drivingly connected to the conveyor 78 via a conveyor drive shaft 88, as shown more clearly in FIG. 3. The conveyor drive shaft 88 drivingly engages a portion of the conveyor 78, generally near the disposing end 84 thereof, and the conveyor drive 86 is, more particularly, drivingly connected to the conveyor drive shaft 88. It will be apparent from the foregoing that the above designations referring to the "receiving end" 82 and the "disposing end" 84 of the conveyor 78, refer more particularly to relative positions, rather than specific portions of the conveyor 78, the designations being used merely for identification and for the purpose of clarity of description.

The conveyor assembly 76 also includes a conveyor control apparatus 90 having a portion thereof connected to the conveyor 78 to automatically adjust the tension of the conveyor 78 to predetermined tension positions, and another portion thereof to sensingly engage a portion of the conveyor 78, and to automatically align the conveyor 78 to a predetermined alignment position, in response to a sensed position of the conveyor 78, in a manner and for reasons which will be described in greater detail below.

In a preferred form, the excavator 10 includes a pair of hydraulic cylinders 91 (shown in dashed-lines in FIG. 3), each hydraulic cylinder 91 being secured to a portion of the support frame 12 and having a portion pivotally secured to a portion of the conveyor support frame 80. The hydraulic cylinders 91 are thus connected to actuatingly lower the conveyor assembly 76 a predetermined distance, in one actuated position thereof, and to actuatingly raise the conveyor assembly 76 a predetermined distance, in one other actuated position thereof. In this manner the angular orientation or elevation of the conveyor assembly 76 can be positioned at an optimum lowermost position, in some instances, to reduce the power consumed by the conveyor drive 86, during the operation of the excavator 10.

As shown in FIGS. 1, 2 and 3, supported on the cutting side 14 of the support frame 12, generally near the forward end 18 thereof, is a forward control console 92 and supported on the cutting side 14 of the support

frame 12, generally near the rearward end 20 thereof, is a rearward control console 94. The forward control console 92 and the rearward control console 94 are each, more particularly, supported on a platform structure 96. In a preferred form, the forward control console 92 and the rearward control console 94 each contain substantially all of the manually-operated, control actuating elements to control various aspects of the excavator 10, and each is constructed and adapted such that an operator can easily control the excavator 10 from either the forward control console 92 or the rearward control console 94.

In a preferred form, when the excavator 10 is moving in the forward direction 40 and the forward portion 68 of the vertical earth removal assembly 66 has been positioned in the earth engaging position thereof, as shown in FIGS. 1, 2 and 3, the operator will control the excavator 10 utilizing the forward control console 92. Utilizing the forward control console 92 to control the excavator 10, the operator is in an optimum position to visually observe obstacles which might lie in the path of the excavator 10, the portion of earth being excavatingly engaged by the forward portion 68 of the vertical earth removal assembly 66 and the forward portion 62 of horizontal earth removal assembly 60, the excavated earth being moved generally onto the receiving end portion 82 of the conveyor 78, and the excavated earth moved along the conveyor 78 generally toward the disposing end 84 thereof to be deposited thereover. When the excavator 10 is moving in the forward direction 40 the operator utilizing the forward control console 92 is thus able to visually observe the operation of the various assemblies and apparatus aspects of the excavator 10 from an optimum vantage point.

Conversely, when the excavator 10 is being moved in the rearward direction 42, an operator, utilizing the rearward control console 94 to control the various apparatus and assemblies of the excavator 10, is also positioned to observe the portion of earth being excavatingly engaged by the rearward portion 70 of the vertical earth removal assembly 66 and the rearward portion 64 of the horizontal earth removal assembly 60, the excavated earth being removed onto the conveyor 78, the excavated earth being moved generally along the conveyor 78 generally toward the disposing end 84 thereof and deposited thereover, and obstacles which might lie in the path of the excavator 10. It should be particularly noted, however, that the excavator 10 can be operated from a single control console or by utilizing either the forward control console 92 or the rearward control console 94 when the excavator 10 is moving in the forward direction 40 and the rearward direction 42.

As shown in FIGS. 1, 2 and 3, a pair of power fluid reservoirs 98 are supported on a portion of the support frame 12, one of the power fluid reservoirs 98 being supported generally near the rearward end 20 of the support frame 12, and the other power fluid reservoir 98 being supported generally near the forward end 18 of the support frame 12. Each power fluid reservoir 98 is sized to retain a predetermined amount of power fluid which is subsequently utilized to drive or control various assemblies, components and apparatus of the excavator 10, during the operation of the excavator 10, as will be described in greater detail below.

OPERATION OF THE PREFERRED EMBODIMENT

The excavator 10 is constructed to excavatingly en-

gage and remove a predetermined portion of earth from a hill or bank-like earth structure in a more efficient and in a more economical manner. Utilizing the grade and slope control apparatus, mentioned above, the operator will initially position the excavator 10, with respect to a horizontal plane, so that the horizontal earth removal assembly 60 and the vertical earth removal assembly 66 will each excavatingly engage and remove a portion of earth in a manner conforming to the preset, controlled grade and slope. It should be particularly mentioned, at this point, that the grade and slope control apparatus of the excavator 10, in a preferred form, has a portion which is connected to be actuated by the operator to control the grade, and another portion which is constructed to be automatically actuated, in response to a predetermined slope signal, thereby maintaining the excavator 10 in a controlled position wherein the horizontal earth removal assembly 60 and the vertical earth removal assembly 66 will excavatingly remove a portion of earth in accordance with the preset slope control signal, in a manner and for reasons which will be made more apparent below.

For the purpose of describing the operation of the excavator 10, it will be assumed that the excavator 10 is to be initially positioned near a bank-like earth structure to excavatingly engage a portion thereof while moving in a forward direction 40. After the excavator 10 has been initially positioned generally adjacent to the bank-like structure, the operator will actuate the forward positioning assembly 72, to position the forward portion 68 of the vertical earth removal assembly 66 in an earth engaging position, as shown in FIGS. 1 and 2, and will actuate the rearward actuating assembly 74 to move the rearward portion 70 of the vertical earth removal assembly 66 to the storage position thereof.

The operator will then actuate the conveyor control apparatus 90 to automatically adjust the tension of the conveyor 78 to a predetermined unloaded tension thereof. The conveyor control apparatus 90 is constructed to automatically maintain a predetermined alignment of the conveyor 78, during the operation of the excavator 10, in a manner which will be described in greater detail below.

Diagrammatically shown in FIG. 4, and designated by the general reference numeral 100, is a cross-section of a hill or bank-like earth structure, which will be referred to below for the purpose of more clearly describing the operation of the excavator 10. Thus, the excavator 10 will be positioned generally adjacent the bank-like earth structure 100 in a position wherein the forward portion 62 of the horizontal earth removal assembly 60 will be positioned to excavatingly engage and remove a portion of the bank-like earth structure 100, designated in FIG. 4 by the general reference numeral 102 and referred to below as a "horizontal section of earth structure", for the purpose of clarity of description. Also, in this position of the excavator 10, the forward portion 68 of the vertical earth removal assembly 66 is positioned adjacent to the bank-like structure 100 to excavatingly engage and remove a portion of earth, designated in FIG. 4 by the general reference numeral 104 and referred to generally below as a "vertical section of earth structure", for the purpose of clarity of description.

As the excavator 10 is driven in a forward direction 40 to excavatingly engage and remove the horizontal

section of earth structure 102 and the vertical section of earth structure 104, the excavated earth will be guidingly moved to the receiving end 82 of the conveyor 78. In an operating position of the excavator 10, the conveyor 78 is being continually driven by the conveyor drive 86 and, thus, the excavated earth moved onto the receiving end 82 of the conveyor 78 will be continually moved generally up the conveyor 78 toward the disposing end 84 thereof, and dropped or deposited thereover in a predetermined position as, for example, in the bed of a truck to be subsequently removed to a land fill or other such remote location.

When the excavator 10 has been moved in a forward direction 40 a predetermined distance to complete one pass along the bank-like earth structure 100, the operator will stop the excavator 10, and position the excavator 10 to make a subsequent pass along the bank-like earth structure 100. The operator will initially move the excavator 10 in a forward direction 40, a distance generally beyond the bank-like earth structure 100, prior to making a subsequent or second pass along the bank-like earth structure 100 in the rearward moving direction 42 of the excavator 10.

To position the excavator 10 to excavatingly engage the bank-like earth structure 100 in a rearward moving direction 42 thereof, the operator will actuate the forward positioning assembly 72 to position the forward portion 68 of the vertical earth removal assembly 66 to a storage position thereof, and will actuate the rearward positioning assembly 74 to move the rearward portion 70 of the vertical earth removal assembly 66 to an earth engaging position thereof. The operator will then maneuver the excavator 10 in a rearward direction to a position generally adjacent to the bank-like earth structure 100, wherein the rearward portion 64 of the horizontal earth removal assembly 60 is disposed to excavatingly engage a horizontal section of the earth structure, designated in FIG. 4 by the reference numeral 102a, and to a position wherein the rearward portion 70 of the vertical earth removal assembly 66 is disposed to excavatingly engage a vertical section of the structure, designated in FIG. 4 by the reference numeral 104a. The excavator 10 will then be moved in the rearward direction 42 to excavate the horizontal section of earth structure 102a and to excavate the vertical section of earth structure 104a.

After the excavator 10 has been moved in the rearward direction 42 a sufficient distance to complete the second pass along the bank-like earth structure 100, the operator will again actuate the forward positioning assembly 72 and the rearward positioning assembly 74, to move the forward portion 68 of the vertical earth removal assembly 66 to an earth engaging position, and to move the rearward portion 70 of the vertical earth removal assembly 66 to a storage position, and will maneuver the excavator 10, in a manner as described before, to excavatingly engage the bank-like earth structure 100 in a forward moving direction 40 of the excavator 10.

The operation, generally described above, is repeated a predetermined number of times until the required portion of earth has been excavatingly removed. If, for example, a particular job specification requires the bank-like earth structure 100 to be excavated to a position generally designated in FIG. 4 by the general reference numeral 106, the excavator 10 will be excavatingly moved in a forward direction 40 and in a

rearward direction 42 to excavatingly remove the horizontal sections of earth structure 102, 102a, 102b and 102c, and to excavatingly remove the vertical sections of earth structure 104, 104a, 104b and 104c.

The conveyor assembly 76 is disposed on the excavator 10 to receive the excavated earth moved thereon and move the excavated earth generally over the disposing end 84 thereof in a forward moving direction 40 of the excavator 10 and in a rearward moving direction 42 of the excavator 10, as mentioned before. Thus, virtually the only control adjustments which must be made by the operator, after each excavating pass along the bank-like earth structure 100, are to actuate the forward positioning assembly 72 and the rearward positioning assembly 74 to position the vertical earth removal assembly 66 to the proper earth engaging position, prior to making a subsequent excavating pass along the bank-like earth structure 100 in the forward moving direction 40 or the rearward moving direction 42 of the excavator 10, and, of course, to reverse the direction in which each of the endless track members 23 is driven.

Thus, the excavator 10 is constructed to be positioned to make subsequent excavating passes along the bank-like earth structure 100, in a faster, more efficient, more economical manner, and in a manner substantially eliminating the need for maneuvering the earth working apparatus to the initial starting position (which in many instances would be a considerable distance from the terminating position) or, in the alternative, eliminating the need for turning the earth working apparatus 180 degrees prior to making subsequent passes along the bank-like earth structure 100. The conveyor assembly 76 is supported on the excavator 10, and is disposed with respect to the horizontal earth removal assembly 60 and the vertical earth removal assembly 66 to receive the excavated earth deposited thereon and to move same to a predetermined disposing area, in a forward moving direction 40 and a rearward moving direction 42 of the excavator 10, in such a manner that the conveyor assembly 76 remains in a predisposed position, thereby eliminating the necessity for reorienting an earth removal apparatus to receive and remove excavated earth prior to utilizing the excavator 10 to make subsequent excavating passes.

It should also be noted that, during the operation of the excavator 10, the grade and slope apparatus maintains the excavator 10 or, in other words, the support frame 12, in a predetermined grade and slope position with respect to a horizontal plane by automatically actuating the first forward hydraulic cylinders 44, 46 and 48, the second forward hydraulic cylinder 50, the first rearward hydraulic cylinders 52, 54 and 56, and the second rearward hydraulic cylinder 58.

HORIZONTAL AND VERTICAL EARTH REMOVAL ASSEMBLY

The horizontal earth removal assembly 60, more particularly, includes a forward horizontal digging implement 110 which is connected to the cutting side 14 of the support frame 12 or, more particularly, to a lowermost portion of the forward portion 62 thereof. The forward horizontal digging implement 110 basically includes a plurality of digging teeth 112, as shown more clearly in FIGS. 1 and 3. The digging teeth 112 are horizontally disposed in a spaced relationship along a lowest end portion of a forward earth lifting member

114. The forward earth lifting member 114 is connected to the cutting side 14 of the support frame 12, and is disposed on an inclined plane, oriented such that the portion of earth engaged thereby, in a forward moving direction 40 of the excavator 10, is moved generally up the inclined plane and over the upper end thereof, during the operation of the excavator 10.

The rearward portion 64 of the horizontal earth removal assembly 60 includes a rearward horizontal digging implement 116, which is connected to the cutting side 14 of the support frame 12 or, more particularly, to a lowermost portion of the rearward portion 64 thereof. The rearward horizontal digging implement 116, as shown more clearly in FIGS. 1 and 3, basically includes a plurality of digging teeth 118. The digging teeth 118 are, more particularly, horizontally disposed in a spaced relationship along a lowermost portion of a rearward earth lifting member 120. The rearward earth lifting member 120 is also connected to the cutting side 14 of the support frame 12 and is disposed on an inclined plane, oriented such that the portion of earth engaged thereby, in a rearward moving direction 42 of the excavator 10 is moved generally up the inclined plane and over the upper end thereof, during the operation of the excavator 10.

The uppermost end of the forward earth lifting member 114 and the rearward earth lifting member 120 are spaced a distance apart and connected via a horizontally disposed plate 122, as shown more clearly in FIGS. 1 and 3. More particularly, the forward earth lifting member 114 and the rearward earth lifting member 120 are spaced a predetermined distance apart such that the receiving end portion 82 of the conveyor assembly 76 can be operably disposed therebetween. Thus, the receiving end 82 of the conveyor assembly 76 is disposed between the forward earth lifting member 114 and the rearward earth lifting member 120, to receive the excavated earth therefrom in a forward moving direction 40 and in a rearward moving direction 42 of the excavator 10.

The forward earth lifting member 114 and the rearward earth lifting member 120, each extend a predetermined distance from the cutting side 14 of the support frame 12, terminating with an outermost portion 124. The outermost portion 124 of the forward earth lifting member 114 and the rearward earth lifting member 120 are each connected via a vertically disposed plate 126, as shown more clearly in FIGS. 1 and 2. The plate 126, not only provides additional structural support for the horizontal earth removal assembly 60, but also provides a baffle which prevents the excavated earth from being moved generally under the horizontal earth removal assembly 60, and thus cooperates to guide the excavated earth onto the receiving end 82 of the conveyor 78.

More particularly, the forward earth lifting member 114 and the rearward earth lifting member 120, each extend a distance 128 from the support frame 12, which defines the width of the horizontal section of earth structure excavatingly removed by the forward horizontal digging implement 110 and the forward earth lifting member 114 associated therewith, in a forward moving direction 40 of the excavator 10, and the width of the horizontal section of earth structure excavatingly removed by the rearward horizontal digging implement 116 and the rearward earth lifting member 120 associated therewith, in a rearward moving direc-

tion 42 of the excavator 10, as shown more clearly in FIG. 3 and as diagrammatically shown in FIG. 4 with respect to the horizontal section of earth structure 102b.

The height or the vertical distance 130 generally between the upper end and the lower end of the forward earth lifting member 114 and the rearward earth lifting member 120, as shown more clearly in FIGS. 1 and 2, defines the vertical height of the horizontal section of earth structure excavatingly removed by the forward earth lifting member 114 and the forward horizontal digging implement 116 connected thereto, and the rearward earth lifting member 120 and the rearward horizontal digging implement 116 connected thereto, in a forward moving direction 40 and in a rearward moving direction 42, respectively, of the excavator 10. The vertical height of the horizontal section of earth structure removed by the horizontal earth removal assembly 60, as described above, is diagrammatically shown in FIG. 4 with respect to the horizontal section of earth structure 102b. In a preferred form, the horizontal earth removal assembly 60 is constructed such that the vertical height 130 of the horizontal section of earth structure excavatingly removed thereby is maintained at a minimum predetermined vertical height, the minimum predetermined vertical height being that vertical height sufficient for the conveyor assembly 76 to be operably disposed between the forward earth lifting member 114 and the rearward earth lifting member 120, as described before. In this manner, less power is consumed by the excavator 10 per cubic yard of earth excavated, since the maximum amount of earth is excavated by the vertical earth removal assembly 66 wherein such excavated earth is aided by gravity in falling onto the conveyor assembly 76.

As shown more clearly in FIGS. 1 and 2, the excavator 10 also includes a forward baffle member 132, having an upper end 134 and a lower end 136. The forward baffle member 132 is connected to one side of the forward earth lifting member 114, generally opposite the outermost portion 124 thereof, and has a portion thereof which extends a distance generally from the forward earth lifting member 114 toward the forward end 18 of the support frame 12. The lower end 136 of the forward baffle member 132 is disposed in a horizontal plane, generally coplanar with the lower end portion of the horizontal earth removal assembly 60, and the upper end 134 of the forward baffle member 132 extends a distance vertically above the forward earth lifting member 114. The forward baffle member 132 is thus sized and positioned to cooperate with the forward earth lifting member 114 to channel a portion of the excavated earth generally up the forward earth lifting member 114 and onto the receiving end 82 of the conveyor 78.

The excavator 10 also includes a rearward baffle member 138, having an upper end 140 and a lower end 142, as shown more clearly in FIGS. 1 and 2. The rearward baffle member 138 is connected to one side of the rearward earth lifting member 120, generally opposite the outermost portion 124 thereof, and has a portion thereof which extends a distance generally from the rearward earth lifting member 120 toward the rearward end 20 of the support frame 12. The lower end 142 of the rearward baffle member 138 is substantially coplanar with the lowermost portion of the horizontal earth removal assembly 60, and the upper end 140 of the

rearward baffle member 138 extends a distance vertically above the rearward earth lifting member 120. The rearward baffle member 138 is thus sized and shaped to cooperate with the rearward earth lifting member 120 to channel a portion of the excavated earth generally up the rearward earth lifting member 120 and onto the receiving end 82 of the conveyor 78.

The vertical earth removal assembly 66 includes a forward vertical digging implement 150 which is connected to the cutting side 14 of the support frame 12. The forward vertical digging implement 150 basically includes a plurality of spaced digging teeth 152 which are constructed and disposed to excavatingly engage a portion of earth generally along a predetermined vertical plane, in a forward moving direction 40 of the support frame 12, as shown more clearly in FIGS. 1 and 2.

The vertical earth removal assembly 66 also includes a rearward digging implement 154 which is connected generally to the cutting side 14 of the support frame 12. As shown more clearly in FIGS. 1 and 2, the rearward digging implement 154 also basically includes a plurality of spaced digging teeth 156 which are constructed and disposed to excavatingly engage a portion of earth, generally along a predetermined vertical plane, in a rearward moving direction 42 of the support frame 12.

The forward digging implement 150 and the rearward digging implement 154 are, more particularly, connected to a forward frame 158 and a rearward frame 160, respectively. The forward frame 158 and the rearward frame 160 each include an earth engaging face 162, an upper end 164, a lower end 166, a cutting side 168 and a pivot side 170. The forward vertical digging implement 150 is, more particularly, connected to the cutting side 168 of the forward frame 158, and the rearward digging implement 154 is, more particularly, connected to the cutting side 168 of the rearward frame 160.

As shown more clearly in FIG. 3, the pivot side 170 of the forward frame 158 is pivotally secured to the cutting side 14 of the support frame 12 via a pivot member 172, and the pivot side 170 of the rearward frame 160 is pivotally secured to the cutting side 14 of the support frame 12 via a pivot member 174. The forward frame 158 is thus pivotable in a pivot direction 176 and in a pivot direction 178, generally about the pivot member 172, and the rearward frame 160 is pivotable in a pivot direction 180 and in a pivot direction 182, generally about the pivot member 174. More particularly, the forward frame 158 and the rearward frame 160 are each pivotable to an earth engaging position and to a storage position, in a manner and for reasons to be described in greater detail below.

As shown more clearly in FIG. 2, the forward frame 158 is sized and pivotably supported on the support frame 12 such that the lower end 166 thereof is disposed in a predetermined horizontal plane, which is substantially coplanar with the upper end of the rearward earth lifting member 120, yet allowing a clearance therebetween so that the forward frame 158 and the forward vertical digging implement 150 connected thereto can be pivotally moved generally over the upper end of the rearward earth lifting member 120 to an earth engaging position, as shown in FIGS. 1, 2 and 3, and to a storage position as shown in FIGS. 1, 2 and 3, with respect to the rearward frame 160. The rearward frame 160 is also sized and pivotably supported on the support frame 12 such that the lower end 166

thereof is disposed in a predetermined horizontal plane, substantially coplanar with the upper end of the forward earth lifting member 114, yet allowing a clearance therebetween for the rearward frame 160 and the rearward digging implement 154 to be pivoted generally over the upper end of the forward earth lifting member 114, to an earth engaging position, as shown in FIGS. 1, 2 and 3, with respect to the forward frame 158, and to a storage position, as shown in FIGS. 1, 2 and 3.

The width of the forward frame 158 and the rearward frame 160, generally between the pivot side 170 and the cutting side 168 of each of the frames 158 and 160, is sized to support the forward digging implement 150 and the rearward digging implement 154, respectively, in a predetermined vertical cutting plane, spaced a predetermined distance 184 from a vertical plane, substantially coplanar with the outermost portions 124 of the forward earth lifting member 114 and the rearward earth lifting member 120. The distance 184 between the forward vertical digging implement 150 and the rearward vertical digging implement 154 and the outermost portions 124, described before, is shown more clearly in FIG. 3 with respect to the forward frame 158.

The distance 184, more particularly, defines the width of the vertical section of earth structure excavatingly removed by the forward vertical digging implement 150 and the rearward digging implement 154 when such vertical digging implement 150 and 154 has been pivoted to the earth engaging position, as shown in FIGS. 1, 2 and 3, with respect to the forward vertical digging implement 150. The width 184 of the portion of earth excavatingly engaged by the forward vertical digging implement 150 or rearward vertical digging implement 154 is diagrammatically shown in FIG. 4, with respect to the vertical section of earth structure 104b.

The vertical distance, generally between the upper end 164 and the lower end 166 of the forward frame 158 and the forward digging implement 150 connected thereto, and the rearward frame 160 and the rearward digging implement 154 connected thereto defines substantially the height of the vertical section of earth structure removed by the vertical earth removal assembly 66, in a forward moving direction 40 and in a rearward moving direction 42 of the excavator 10. In a preferred form, and as mentioned before, the vertical height of the forward frame 158 and the rearward frame 160 is sized such that the vertical earth removal assembly 66 excavatingly engages and removes a maximum portion of the earth excavated during each pass of the excavator 10 moving in a forward direction 40 and in a rearward direction 42, thereby reducing the power consumed by the excavator 10 per cubic yard of earth excavated.

It should also be noted that the lower end 166 of the forward frame 158 is shaped to be pivotally moved over the upper end 140 of the rearward baffle member 138 to a storage position wherein the earth engaging face 162 thereof is substantially coplanar with the rearward baffle member 138, thereby cooperating with the rearward baffle member 138 to channel a portion of the excavated earth onto the conveyor 78. The lower end 166 of the rearward frame 160 is shaped to be pivotally moved over the upper end 134 of the forward baffle member 132 to a storage position of the rearward frame 160 wherein the earth engaging face 162 thereof is substantially coplanar with the forward baffle mem-

ber 132, thereby cooperating with the forward baffle member 132 to channel a portion of the excavated earth onto the conveyor 78.

As mentioned before, the vertical earth removal assembly 66 includes a forward positioning assembly 72 and a rearward positioning assembly 74, each of which are constructed to position a portion of the vertical earth removal assembly 66 in an earth engaging position or in a storage position. The forward positioning assembly 72 and the rearward positioning assembly 74 are constructed similar and each includes a hinge member pivotally connecting the vertical earth removal assembly 66 to the support frame 12, and a hydraulic cylinder actuator connected to the support frame 12 and to the hinge member, in such a manner that the forward portion 68 and the rearward portion 70 of the vertical earth removal assembly 66 can each be selectively positioned in an earth engaging position or in a storage position, during the operation of the excavator 10.

The forward positioning assembly 72 includes a first hinge member 188, having one side thereof pivotally secured to a portion of the forward frame 158 via a pivot member 190, generally along a face thereof, opposite the earth engaging face 162, as shown more clearly in FIG. 3. A second hinge member 192 has one side thereof pivotally secured to the side of the first hinge member 188, generally opposite the side thereof which is pivotally secured to the forward frame 158, via a pivot member 194. The side of the second hinge member 192, generally opposite the side thereof pivotally secured to the first hinge member 188, is pivotally secured to the cutting side 14 of the support frame 12 via a pivot member 196.

The forward positioning assembly 72, as shown more clearly in FIGS. 3 and 5, also includes a pair of hydraulic cylinders 198 and 200. Each hydraulic cylinder 198 and 200 has a portion thereof which is pivotally connected to the support frame 12, and a rod member 202 which is reciprocatingly disposed therein. The end of each rod member 202, opposite the end thereof, which is reciprocatingly disposed in one of the hydraulic cylinders 198 and 200, is pivotally secured to a portion of the second hinge member 192, for reasons which will be made more apparent below.

The rearward positioning assembly 74 includes a first hinge member 204, as shown more clearly in FIG. 3, which is pivotally secured to a portion of the rearward frame 160, generally along a face, opposite the earth engaging face 162 thereof, via a pivot member 206. One side of a second hinge member 208 is pivotally secured to the side of the first hinge member 204, opposite the side thereof pivotally secured to the rearward frame 160, via a pivot member 210. The side of the second hinge member 208, opposite the side thereof which is pivotally secured to the first hinge member 204, is pivotally secured to the cutting side 14 of the support frame 12 via a pivot member 212.

The rearward positioning assembly 74 also includes a pair of hydraulic cylinders 214 and 216, a portion of each hydraulic cylinder 214 and 216 being pivotally secured to a portion of the support frame 12, as shown more clearly in FIG. 5. Each hydraulic cylinder 214 and 216 has a rod member 218 reciprocatingly disposed therein, and the end of each rod member, opposite the end thereof reciprocatingly disposed in one of the hydraulic cylinders 214 or 216, is pivotally secured

to a portion of the second hinge member 208, as shown in FIGS. 2 and 5.

The hydraulic cylinders 198 and 200 of the forward positioning assembly 72 and the hydraulic cylinders 214 and 216 of the rearward positioning assembly 74, each have one actuated position wherein the rod member 202 or 218 disposed therein is reciprocatingly extended therefrom in a general direction 220, as shown in FIG. 5, and one other actuated position wherein the rod members 202 and 218 reciprocatingly disposed therein are moved in a general direction 222, as shown more clearly in FIG. 5. When the hydraulic cylinders 198 and 200 of the forward positioning assembly 72 are actuated to move the rod members 202 in a direction 220, the second hinge member 192 connected thereto will be moved in a direction generally away from the cutting side 14 of the support frame 12, thereby pivoting the forward frame 158 in a pivot direction 176, generally toward an earth engaging position thereof, as shown in FIGS. 1, 2 and 3.

The first hinge member 188 and the second hinge member 192 are each sized and pivotally connected, and the hydraulic cylinders 198 and 200 are each positioned such that the first hinge member 188 and the second hinge member 192 are positioned in a substantially coplanar relationship, in an earth engaging position of the forward vertical digging implement 150, as shown in FIGS. 1, 2 and 3. In this manner, the digging load imposed on the forward digging implement 150 and the forward frame 158, as the excavator 10 is being moved in a generally forward direction 40, will be transmitted through the first hinge member 188 and the second hinge member 192 and carried therethrough by the support frame 12. Thus, the digging load is, for the most part, not imposed on the hydraulic cylinders 198 and 200, thereby decreasing the size requirements of the hydraulic cylinders 198 and 200, and substantially decreasing the wearing thereof and reducing the maintenance downtime for repair or replacement thereof.

The first hinge member 204 and the second hinge member 208 are also each sized and pivotally connected, and the hydraulic cylinders 214 and 216 are each positioned such that the first hinge member 204 and the second hinge member 208 are positioned in a substantially coplanar relationship, in an earth engaging position of the rearward digging implement 154, in a manner similar to that described above with respect to the first hinge member 188 and the second hinge member 192. The digging load imposed on the rearward digging implement 154 and the rearward frame 160, as the excavator 10 is being moved in a generally rearward direction 42, is thus transmitted through the first hinge member 204 and the second hinge member 208 and carried therethrough by the support frame 12, thereby decreasing the size requirements of the hydraulic cylinders 214 and 216, and decreasing the wearing thereof and reducing the maintenance downtime for the excavator 10.

CONVEYOR CONTROL APPARATUS

Diagrammatically shown in FIG. 6 is a fragmentary portion of the conveyor assembly 76, generally near the disposing end 84 of the conveyor 78 and schematically shown in FIG. 6 is the conveyor control apparatus 90 having one portion constructed to sensingly engage a portion of the conveyor 78 and to automatically align the conveyor 78 to a predetermined alignment posi-

tion, and one other portion connected to the conveyor 78 and constructed to automatically adjust the tension of the conveyor 78 to predetermined tension positions.

The conveyor drive 86 is also shown in FIG. 6 and, more particularly, includes a pair of hydraulic motors 230, one hydraulic motor 230 being connected to one end of the conveyor drive shaft 88 and the other hydraulic motor 230 being connected to the opposite end of the conveyor drive shaft 88. More particularly, one end of the conveyor drive shaft 88 extends through a slot 232 formed through one side of the conveyor support frame 80, and the opposite end of the conveyor drive shaft 88 extends through a similar slot 234 formed through the opposite side of the conveyor support frame 80. It will be apparent to those skilled in the art from the foregoing, that the conveyor drive shaft 88 and the hydraulic motors 230 connected thereto are movable in a tension increasing direction 236 and in a tension decreasing direction 238, generally within the slots 232 and 234, thereby moving the conveyor 78 in a tension increasing direction 236 and in a tension decreasing direction 238, for reasons and in a manner to be described in greater detail below.

The conveyor control apparatus 90 includes a first hydraulic cylinder 240 and a second hydraulic cylinder 242, the first hydraulic cylinder 240 being secured to one side of the conveyor support frame 80 via a support member 244, and the second hydraulic cylinder 242 being secured to the opposite side of the conveyor support frame 80 via a support member 246, as shown in FIG. 6. The first hydraulic cylinder 240 and the second hydraulic cylinder 242, each include a rod portion 248 which is reciprocatingly disposed therein, and the end of each rod member 248, generally opposite the end thereof which is reciprocatingly disposed in one of the hydraulic cylinders 240 or 242, is secured to one of the hydraulic motors 230 or, more particularly, to a flange portion 250 (one flange 250 being formed on a portion of each hydraulic motor 230). The rod portions 248 of the first hydraulic cylinder 240 and the second hydraulic cylinder 242 are each thus connected to the conveyor 78 via the hydraulic motors 230 and the conveyor drive shaft 88. The first hydraulic cylinder 240 and the second hydraulic cylinder 242 are each thus connected to the conveyor support frame 80 and, more particularly, to the conveyor drive shaft 88, to move the conveyor 78 in a tension increasing direction 236, in one actuated position of the first hydraulic cylinder 240 and the second hydraulic cylinder 242, and to move the conveyor 78 in a tension decreasing direction 238, in one other actuated position of the first hydraulic cylinder 240 and the second hydraulic cylinder 242.

In a preferred form, the conveyor 78 is securely supported in a stationary position relative to the conveyor support frame 80 generally near the receiving end 82 of the conveyor 78. Thus, as the conveyor 78 is moved in a tension increasing direction 236 by so moving the conveyor drive shaft 88, the tension imposed on the conveyor 78 will be increased and, as the conveyor 78 is moved in a tension decreasing direction 238 by so moving the conveyor drive shaft 88, the tension imposed on the conveyor 78 will be increasingly decreased. It should be noted that, in one other form, the end of the conveyor 78 which is in driving engagement with the hydraulic motors 230 could be stationarily positioned, and the conveyor control apparatus 90 could be connected to the opposite end of the conveyor 78,

which would be movably supported via a shaft extending through slots, similar to the slots 232 and 234.

The hydraulic motors 230 are each connected to a variable pump 252 via a conduit 254, the variable pump 252 being actuated to provide power fluid to drive the hydraulic motors 230 via a pump drive 256, which is connected thereto. The power fluid provided to drive each hydraulic motor 230 is returned to a power fluid reservoir 258 via a conduit 260, as schematically shown in FIG. 6. The conveyor drive 86 thus, in one aspect, includes the hydraulic motors 230, the variable pump 252 and the pump drive 256, all of which are connected to drivingly move the conveyor 78 during the operation of the excavator 10, in a manner as generally described above.

As shown in FIG. 6, a pump 262 is hydraulically connected to the first hydraulic cylinder 240 and to the second hydraulic cylinder 242 via a conduit 263. As schematically indicated in FIG. 6, the conduit 263 is connected to each hydraulic cylinder 240 and 242 such that power fluid provided therethrough via the pump 262 will actuate the hydraulic cylinders 240 and 242 to move the rod portions 248 in a tension increasing direction 236, thereby moving the conveyor 78 in a tension increasing direction 236.

A pressure control valve 264 is interposed in the conduit 263, generally between the pump 262 and the first hydraulic cylinder 240 and the second hydraulic cylinder 242. The pressure control valve 264 is constructed to establish fluidic communication between the pump 262 and the hydraulic cylinders 240 and 242, in an energized position of the pressure control valve 264, and to interrupt fluidic communication between the pump 262 and the hydraulic cylinders 240 and 242, in a de-energized position of the pressure control valve 264.

As shown in FIG. 6, a power fluid source 270 is hydraulically connected to a portion of the first hydraulic cylinder 240 and to the portion of the second hydraulic cylinder 242, to actuate the first hydraulic cylinder 240 and the second hydraulic cylinder 242 to move the rod portions 248 in a tension decreasing direction 238, thereby moving the conveyor 78 in a tension decreasing direction 238. A solenoid-operated alignment control valve 272 is interposed between the power fluid source 270 and the first hydraulic cylinder 240 and the second hydraulic cylinder 242, and a solenoid-operated dump valve 274 is interposed between the alignment control valve 272 and the power fluid source 270, in a manner and for reasons which will be described in greater detail below.

The alignment control valve 272, as schematically indicated in FIG. 6, has a de-energized position 276, a first energized position 278 and a second energized position 280. The dump valve 274, as schematically indicated in FIG. 6, has a de-energized position 282 and an energized position 284. The alignment control valve 272 and the dump valve 274 cooperate to selectively provide power fluid to the first hydraulic cylinder 240, in one position of the conveyor control apparatus 90, and to provide power fluid to the second hydraulic cylinder 242, in one other position of the conveyor control apparatus 90, and to dump the power fluid provided to the first hydraulic cylinder 240 and the second hydraulic cylinder 242 via the power fluid source 270, in another position of the conveyor control apparatus 90, in a manner to be described in greater detail below.

As shown in FIG. 6, a conduit 286 fluidically connects a portion of the first hydraulic cylinder 240 to the alignment control valve 272, and another conduit 288 fluidically connects the second hydraulic cylinder 242 to the alignment control valve 272. A pair of conduits 290 and 292 connect the alignment control valve 272 to the dump valve 274. A conduit 294 connects the power fluid source 270 to the dump valve 274, and a conduit 296 connects the dump valve 274 to the power fluid reservoir 258.

As schematically shown in FIG. 6, the alignment control valve 272 interrupts the fluidic communication between the power fluid source 270 and the first hydraulic cylinder 240 and the second hydraulic cylinder 242, in the de-energized position 276 thereof; establishes fluidic communication between the power fluid source 270 and the first hydraulic cylinder 240, in the first energized position thereof; and establishes fluidic communication between the power fluid source 270 and the second hydraulic cylinder 242 in the second energized position 280 thereof, when the dump valve 274 is in the de-energized position 282. In the de-energized position 282 of the dump valve 274, fluidic communication is established between the power fluid source 270 and the alignment control valve 272. In the energized position 284 of the dump valve 274, fluidic communication between the power fluid source 270 and the alignment control valve 272 is interrupted, and fluidic communication is established between the first hydraulic cylinder 240, the second hydraulic cylinder 242 and the power fluid reservoir 258, when the alignment control valve 278 is in the first energized position 278 or in the second energized position 280, thereby dumping the power fluid from the first hydraulic cylinder 240 and the second hydraulic cylinder 242 to the power fluid reservoir 258, for reasons which will be made more apparent below.

The conveyor control apparatus 90 includes a power supply 300, an alignment switch 302, a sensor 304, a drive control switch 306 and a control switch 308. The alignment switch 302, the sensor 304, the drive control switch 306 and the control switch 308 are each connected to the power supply 300 and to the alignment control valve 272 and to the dump valve 274, to selectively position the alignment control valve 272 and the dump valve 274 to automatically align the conveyor 78 to predetermined alignment positions, in response to a sensed position of the conveyor 78, in a manner which will be described in greater detail below.

As shown in FIG. 6, the control switch 308 includes a switch arm 310, which is positionable to a "Run" position, an "off" position and a "tension" position. The switch arm 310 is connected to the power supply 300 via a conductor 312. The alignment switch 302 includes a pair of switch arms 314 and 316, each switch arm 314 and 316 being connected to the "Run" position of the control switch 308 via a conductor 318. The alignment switch 302 and, more particularly, the switch arms 314 and 316 thereof are positionable in a first position, wherein the switch arm 314 engages a contact 320, and a second position, wherein the switch arm 316 engages a contact 322, for reasons and in a manner to be described in greater detail below.

The sensor 304 is positioned to sensingly engage a portion of the conveyor 78, as schematically indicated in FIG. 6, and is mechanically connected to the switch arms 314 and 316, to position the switch arms 314 and

316 in a disconnect position of the alignment switch 302, that is a position wherein neither the contact 320 nor the contact 322 is engaged by the switch arm 314 of the switch arm 316, and to position the alignment switch 302 in the first position thereof and in the second position thereof. The sensor 304 thus controls the position of the alignment switch 302 and cooperates therewith to selectively actuate the first hydraulic cylinder 240 or the second hydraulic cylinder 242 to move the conveyor 78 to a predetermined alignment position, in a manner which will be described in greater detail below.

The contact 320 of the alignment switch 302 is connected to the alignment control valve 272 via a conductor 324 to energize the alignment control valve 272 to the second energized position 280 thereof, in the first position of the alignment switch 302. The contact 322 of the alignment switch 302 is connected to the alignment control valve 272 via a conductor 326 to energize the alignment control valve 272 to the first energized position 278 thereof, in the second position of the alignment switch 302. When the alignment switch 302 is in the disconnect position, as shown in FIG. 6, electrical continuity between the power source 300 and the alignment control valve 272 will be interrupted, thereby moving the alignment control valve 272 to the de-energized position 276 thereof.

A conductor 328 connects the "tension" position of the control switch 308 to the conductor 324, generally between the alignment control valve 272 and the alignment switch 302. A diode 330 is interposed in the conductor 328, for reasons which will be made more apparent below.

A conductor 332 is connected to the conductor 328, generally between diode 330 and the connection thereof to the "tension" position of the control switch 308. The conductor 332 is also connected to the dump valve 274, thereby providing electrical communication between the "tension" position of the control switch 308 and the dump valve 274 to energize the dump valve 274, in one position of the control switch 308, for reasons which will become more apparent below.

A conductor 333 is connected to the conductor 328 generally between the diode 330 and the connection thereof to the "tension" position of the control switch 308. The conductor 333 is also connected to the pressure control valve 264, thereby providing electrical communication between the tension position of the control switch 308 and the pressure control valve 264 to energize the pressure control valve 264 to establish fluidic communication between the pump 262 and the hydraulic cylinders 240 and 242, for reasons which will become more apparent below.

The drive control switch 306 is mechanically connected to the pump drive 256 to position the drive control switch 306 in the closed position thereof, when the pump drive 256 is actuated to drive the variable pump 252, thereby providing power fluid to the hydraulic motors 230; and to position the drive control switch 306 in the open position thereof, when the pump drive 256 is not driving the hydraulic motors 230. In one form, the drive control switch 306 can also be mechanically connected to the pump drive 256, to position the drive control switch 306 in the opened position thereof, when the pump drive 256 indicates that the variable pump 252 is driving the hydraulic motors 230 at a pre-

determined minimum speed, for reasons which will be made more apparent below.

OPERATION OF THE CONVEYOR CONTROL APPARATUS

In the initial start-up position of the excavator 10, the control switch 308, and more particularly, the switch arm 310 thereof will be positioned in the "tension" position thereby energizing the alignment control valve 272, the dump valve 274 and the pressure control valve 264. The power fluid in the upper portions of the hydraulic cylinders 240 and 242 is drained to the power fluid reservoir 258 via the conduits 286, 288, 290, 292 and 296, and via the alignment control valve 272 and the dump valve 274.

In the energized position of the pressure control valve 264, fluidic communication is established between the pump 262 and the first hydraulic cylinder 240 and the second hydraulic cylinder 242. The pump actuator 268 is then actuated to drive the pump 262, thereby providing power fluid to the first hydraulic cylinder 240 and the second hydraulic cylinder 242, to move the rod portions 248 therein in a tension increasing direction 236, thereby moving the conveyor 78 in the tension increasing direction 236. The pressure control valve 264 will maintain fluidic communication between the pump 262 and the first hydraulic cylinder 240 and the second hydraulic cylinder 242, until the pressure level of the power fluid in the conductor 263 indicates that each hydraulic cylinder 240 and 242 has been actuated to move the conveyor 78 to the predetermined tension position. When the conveyor 78 has been moved in the tension increasing direction 236 to the predetermined tension position, the pressure control valve 264 will be closed, thereby interrupting the fluidic communication between the pump 262 and the hydraulic cylinders 240 and 242, in a manner to be made more apparent below.

The pump drive 256 will then be actuated to drive the variable pump 252, to provide power fluid to the hydraulic motors 230 via the conduit 254, thereby drivingly moving the conveyor 78 to receive and remove the excavated earth, during the operation of the excavator 10, as described before. In the actuated position of the pump drive 256 or, in other words, in a driven position of the pump 252, the drive control switch 306 will be moved to the closed position via the mechanical interconnection between the drive control switch 306 and the pump drive 256, as described before.

After the pump drive 256 and the variable pump 252 have been actuated, the switch arm 310 of the control switch 308 will be moved in the "Run" position, thereby de-energizing the alignment control valve 272, the pressure control valve 264 and the dump valve 274. In the "Run" position of the control switch 308, electrical continuity or communication is established between the power source 300 and the switch arms 314 and 316 of the alignment switch 302 via the conductors 312 and 318 and the drive control switch 306. Assuming that the conveyor 78 is initially positioned in the predetermined alignment position thereof, the sensor 304 will position the switch arms 314 and 316 of the alignment switch 302 in the disconnect position thereof, as shown in FIG. 6, thereby interrupting the electrical communication between the alignment control valve 272 and the power source 300.

During the operation of the excavator 10, and more particularly, during the operation of the conveyor assembly 76 thereof, should the conveyor 78 move from the predetermined alignment position in a direction 334, the sensor 304 will actuatingly position the alignment switch 302 in the first position thereof, thereby moving the switch arm 314 to engage the contact 322. In the first position of the alignment switch 302, electrical communication is established therethrough between the power supply 300 and the alignment control valve 272, thereby energizing the alignment control valve 272 to the second energized position 280 thereof.

In the second energized position 280 of the alignment control valve 272, fluidic communication is established between the power fluid source 270 and the second hydraulic cylinder 242 via the conduits 294, 290 and 288. In this position of the alignment control valve 272, fluidic communication is established between the first hydraulic cylinder 240 and the power fluid reservoir 258 via the conduits 286, 292 and 296.

Thus, in the second energized position 280 of the alignment control valve 272, the second hydraulic cylinder 242 moves the conveyor 78 in a tension decreasing direction 238, and the first hydraulic cylinder 240 moves the conveyor 78 in a tension increasing direction 236, thereby tending to move the conveyor 78 in the correcting direction 336 generally toward the predetermined alignment position thereof. When the conveyor 78 has been moved in the correcting direction 336 to the predetermined alignment position thereof, the sensor 304 will actuatingly move the alignment switch 302 to the disconnect position, thereby de-energizing the alignment control valve 272.

Conversely, should the conveyor 78 be moved from the predetermined alignment position thereof in a direction 336, during the operation of the excavator 10, the sensor 304 will position the alignment switch 302 in the second position thereof, wherein the switch arm 316 engages the contact 322. In the second position of the alignment switch 302, electrical communication is established between the power source 300 and the alignment control valve 272 via the conductors 312, 318 and 326, to energize the alignment control valve 272 to the first energized position 278 thereof.

In the first energized position 278 of the alignment control valve 272, the alignment control valve 272 establishes fluidic communication between the power fluid source 270 and the first hydraulic cylinder 240 via the conduits 294, 290 and 286, and establishes fluidic communication between the second hydraulic cylinder 242 and the power fluid reservoir 258 via the conduits 288, 292 and 296.

Thus, in the first energized position of the alignment control valve 272, the first hydraulic cylinder 240 moves the conveyor 78 in a tension decreasing direction 238 and the second hydraulic cylinder 242 moves the conveyor 78 in a tension increasing direction 236, thereby tending to move the conveyor 78 in the correcting direction 334 generally toward the predetermined alignment position thereof. When the conveyor 78 has been moved in the correcting direction 334 to the predetermined alignment position thereof, the sensor 304 will actuatingly move the alignment switch 302 to the disconnect position thereof, thereby de-energizing the alignment control valve 272.

During the operation of the conveyor assembly 76, should the pump drive 256 be disconnected from the

variable pump 252, the drive control switch 306 will be moved to the open position via the mechanical interconnection between the drive control switch 306 and the pump drive 256. When the drive control switch 306 is in the open position, electrical continuity between the power source 300 and the alignment control valve 272 is interrupted, and the alignment switch 302 and the cooperating sensor 304 thereof will no longer automatically actuate the alignment control valve 272. In this manner, the conveyor control apparatus 90 will not continue to move the conveyor 78 in a correcting direction 334 or 336, subsequent to the hydraulic motors 230 being positioned in a non-driven position thereof or, in other words, subsequent to the conveyor 78 being stopped. As mentioned before, and, in a preferred form, the pump drive 256 is also mechanically connected to the drive control switch 306, to open the drive control switch 306 when the pump drive 256 indicates that the conveyor 78 is being driven at a predetermined reduced speed. In this manner, the conveyor control apparatus, and particularly that portion thereof which is adapted to maintain a predetermined alignment conveyor 78, will not continue to function when the conveyor 78 is being driven at a predetermined reduced rate of speed or when the conveyor 78 is stopped. Thus, the conveyor control apparatus 90 is connected in such a manner as to prevent the alignment control portion thereof from over-reacting, and continuing to move the conveyor 78 in a correcting direction 334 or 336 when the conveyor 78 is not being moved at a rate of speed sufficient to effectively be realigned.

The excavator 10 includes a grade and slope control constructed such that the support frame 12 of the excavator 10 is vertically and automatically positionable about three predetermined control positions; two of the control positions being located generally near the cutting side 14 of the support frame 12, and the third control position being located generally near the earth removal side 16 of the support frame 12, and yet the excavator 10 is supported generally at the four-corner positions thereof. Thus, the grade and slope control provides the maximum positionability for the support frame 12, without a loss of supporting integrity. A grade and slope control constructed to operate in a manner described before in cooperation with the excavator 10 is disclosed in detail in the Applicant's U.S. Pat. No. 3,778,912, and a detailed description is not required herein.

Changes may be made in the construction and the arrangement of the various parts or elements of the embodiment as disclosed herein without departing from the invention as defined in the following claims:

What is claimed is:

1. An earth working apparatus for excavating earth and depositing the excavated earth at a predetermined position, comprising:
 a support frame;
 means connected to the support frame excavatingly engaging a portion of earth in one position;
 a conveyor, having a receiving end and a disposing end, movably supported on the support frame, the receiving end disposed near the means excavatingly engaging a portion of the earth receiving the excavated earth and moving the excavated earth deposited thereon to a predetermined position in a driven position thereof;

a conveyor drive drivingly connected to the conveyor drivingly moving the conveyor in an actuated position of the conveyor drive; and,

a conveyor control apparatus having a portion connected to the conveyor for automatically adjusting the tension of the conveyor means to predetermined tension positions and a portion sensingly engaging a portion of the conveyor and automatically aligning the conveyor to predetermined alignment positions in response to the sensed position of the conveyor, comprising:

- a first hydraulic cylinder connected to the conveyor moving the conveyor in a tension increasing direction in one actuated position thereof, and moving the conveyor in a tension decreasing direction in one other actuated position thereof;
- a second hydraulic cylinder connected to the conveyor moving the conveyor in a tension increasing direction in one actuated position thereof, and moving the conveyor in a tension decreasing direction in one other actuated position thereof;
- a pump connected to the first and second hydraulic cylinders actuating the first and second hydraulic cylinders in a position to move the conveyor in a tension increasing direction, when in fluidic communication therewith;
- a pressure control valve interposed between the pump and the first and second hydraulic cylinders establishing fluidic communication therebetween in an energized position thereof;
- a power fluid source connected to the first and second hydraulic cylinders actuating the first and second hydraulic cylinders for moving the conveyor in a tension decreasing direction when in fluidic communication therewith;
- an alignment control valve interposed between the power fluid source and the first and second hydraulic cylinders, having a de-energized position interrupting the fluidic communication between the power fluid source and the first hydraulic cylinder and the second hydraulic cylinder, a first energized position establishing fluidic communication between the power fluid source and the first hydraulic cylinder, and a second energized position establishing fluidic communication between the power fluid source and the second hydraulic cylinder;
- a power supply connected to the pressure control valve and to the alignment control valve;
- an alignment switch interposed between the power supply and the alignment control valve having a first position establishing communication between the power supply and the alignment control valve energizing the alignment control valve to the second energized position thereof, a second position establishing communication between the power supply and the alignment control valve energizing the alignment control valve to the first energized position thereof, and a disconnect position interrupting the communication between the alignment control valve and the power supply; and,
- a sensor connected to the alignment switch having a portion engaging the conveyor and sensing the position of the conveyor, the sensor positioning the alignment switch in the disconnect position in a sensed aligned position of the conveyor, and positioning the alignment switch in the first position in

one sensed position of the conveyor, and positioning the alignment switch in the second position in one other sensed position of the conveyor, thereby selectively actuating the first hydraulic cylinder and the second hydraulic cylinder correctly moving the conveyor maintaining the position of the conveyor at the predetermined alignment position thereof.

2. The earth working apparatus of claim 1 wherein the conveyor control apparatus is defined further to include:

a drive control switch interposed between the power supply and the alignment switch, the drive control switch having an opened and a closed position, and interrupting communication between the power supply and the alignment switch in the open position thereof, the drive control switch being connected to the conveyor drive and being closed in an actuated position of the conveyor drive.

3. The excavator of claim 2 wherein the drive control switch is further defined as being connected to the conveyor drive and opened at a predetermined reduced rate of speed of conveyor; and wherein the conveyor control apparatus is defined further to include:

a dump valve, having an energized position and a de-energized position, connected to the power supply and interposed between the alignment control valve and the power fluid source, the dump valve establishing communication between the power fluid source and the alignment control valve in the de-energized position thereof, and interrupting communication between the power fluid source and the alignment control valve to dump power fluid passing therethrough in the energized position thereof; and

a control switch interposed between the power supply and the alignment switch, having an off position interrupting communication between the alignment switch and the power supply, a run position establishing communication between the alignment switch and the power supply, and a tension position establishing communication between the alignment control valve, the pressure control valve and the power supply energizing the pressure control valve and energizing the alignment control valve to the second energized position thereof, and establishing communication between the power supply and the dump valve energizing the dump valve to the energized position thereof thereby draining the power fluid in the first hydraulic cylinder and the second hydraulic cylinder pumped therein from the power fluid source and establishing communication between the pump and the first hydraulic cylinder and the second hydraulic cylinder via the pressure control valve.

4. The excavator of claim 1 wherein the support frame includes a cutting side, an earth removal side, a forward end and a rearward end, the means excavatingly engaging the earth being disposed on the cutting side of the support frame, the excavator being defined further to include:

a conveyor support frame connected to the support frame and to the conveyor structurally supporting the conveyor, the conveyor support frame and the conveyor supported thereon extending generally from the cutting side to the earth removal side of the support frame.

5. The excavator of claim 4 wherein the conveyor is defined more particularly as an endless belt-like conveyor, and wherein the conveyor support frame includes opposite sides and a slot formed through a portion of each side, the endless belt-like conveyor extending generally between the opposite sides of the conveyor support frame; and wherein the excavator is defined further to include:

a conveyor drive shaft, having opposite end portions, each end portion extending through a portion of 10 one of the slots in the conveyor support frame, at least one of the opposite end portions of the conveyor drive shaft connected to the conveyor drive and a portion of the endless belt-like conveyor near the disposing end of the conveyor extending about 15 a portion of the conveyor drive shaft, the conveyor drive rotatably driving the conveyor drive shaft thereby drivingly moving the conveyor in a driven position of the conveyor drive.

6. The excavator of claim 4 wherein the conveyor 20 drive includes: a pair of hydraulic motors, each hydraulic motor connected to one of the opposite ends of the conveyor drive shaft; and a portion of the first hydraulic cylinder being connected to the conveyor support frame and another portion being connected to one of the hydraulic motors, the other hydraulic motor being connected to the second hydraulic cylinder; and a portion of the second hydraulic cylinder being connected to the support frame and another portion being connected to the other hydraulic motor, the first and the 25 second hydraulic cylinders moving the conveyor via the hydraulic motors and the conveyor drive shaft and a portion of the conveyor drive shaft moving generally within the slots in the conveyor support frame in actuated positions of the first and the second hydraulic cylinders.

7. The excavator of claim 1 wherein the support frame includes a cutting side, an earth removal side, a forward end and a rearward end; and wherein the excavator includes:

drive means connected to the support frame for supporting the support frame and for moving the support frame in a forward direction and in a rearward direction; and

wherein the means excavatingly engaging a portion of 45 the earth includes:

a vertical earth removal assembly connected to the support frame, comprising:

a forward frame, having an earth engaging face, an 50 upper end, a lower end, a pivot side and a cutting side, the pivot side of the forward frame being pivotally secured to the cutting side of the support frame;

a forward vertical digging implement secured to the cutting side of the forward frame, the forward frame and the forward vertical digging implement connected thereto movable to an earth engaging position and to a storage position, the forward vertical digging implement excavatingly engaging a portion of earth generally along a predetermined vertical plane spaced a distance from the cutting side of the support frame in an earth engaging position thereof and in a forward moving direction of the support frame; and

positioning means connected to the forward frame and the forward vertical digging implement connected thereto to position the forward frame and

5

the forward vertical digging implement in an earth engaging position and a storage position.

8. The excavator of claim 7 wherein the vertical earth removal assembly is defined further to include:

a rearward frame, having an earth engaging face, an upper end, a lower end, a pivot side and a cutting side, the pivot side of the rearward frame being pivotally secured to the cutting side of the support frame; and

a rearward vertical digging implement secured to the cutting side of the rearward frame, the rearward frame and the rearward vertical digging implement connected thereto movable to an earth engaging position and to a storage position, the rearward vertical digging implement excavatingly engaging a portion of earth generally along a predetermined vertical plane spaced a distance from the cutting side of the support frame in an earth engaging position thereof and in a rearward moving direction of the support frame; and

wherein the positioning means is defined further to include a portion connected to the rearward frame and to the rearward vertical digging implement connected thereto to position the rearward frame and the rearward vertical digging implement in an earth engaging position and a storage position.

9. The excavator of claim 8 wherein the positioning means is defined further to include:

a first hinge member having one side thereof pivotally secured to a portion of the forward frame; a second hinge member having one side thereof pivotally secured to the side of the first hinge member, opposite the side thereof pivotally secured to the forward frame, the opposite side thereof being pivotally secured to the cutting side of the support frame; and

hydraulic cylinder means, having one portion pivotally connected to the support frame and pivotally connected to the second hinge member, the hydraulic cylinder means moving the second hinge member connected thereto moving the forward frame and the forward vertical digging implement connected thereto to an earth engaging position in one actuated position of the hydraulic cylinder means, the first hinge member and the second hinge member being positioned in a substantially coplanar relationship in an earth engaging position of the forward frame and the forward vertical digging implement connected thereto and the digging load imposed on the forward vertical digging implement being transmitted through the first and the second hinge members connected thereto and carried therethrough by the support frame.

10. The excavator of claim 9 wherein the positioning means is defined further to include:

a first hinge member having one side thereof pivotally secured to a portion of the rearward frame; a second hinge member having one side thereof pivotally secured to the side of the first hinge member, opposite the side thereof pivotally secured to the rearward frame, the opposite side thereof being pivotally secured to the cutting side of the support frame; and

hydraulic cylinder means, having one portion pivotally connected to the support frame and pivotally connected to the second hinge member, the hydraulic cylinder means moving the second hinge

member connected thereto moving the rearward frame and the rearward vertical digging implement connected thereto to an earth engaging position in one actuated position of the hydraulic cylinder means, the first hinge member and the second hinge member being positioned in a substantially coplanar relationship in an earth engaging position

10

of the rearward frame and the rearward vertical digging implement connected thereto and the digging load imposed to the rearward vertical digging implement being transmitted through the first and the second hinge members connected thereto and carried therethrough by the support frame.
